FOREIGN PATENT DOCUMENTS

GB 2129288 B 6/1986

Primary Examiner — Abraham Bahta(74) *Attorney, Agent, or Firm* — Danielson Legal LLC(57) **CLAIM**

The ornamental design for a foldable infant chair, as shown and described.

DESCRIPTION

FIG. 1 shows a perspective view of the foldable infant chair, the foldable infant chair being in an unfolded configuration; FIG. 2 shows the right side view of the foldable infant chair of FIG. 1;

FIG. 3 shows the left side view of the foldable infant chair of FIG. 1;

FIG. 4 shows the front view of the foldable infant chair of FIG. 1;

FIG. 5 shows the back view of the foldable infant chair of FIG. 1;

FIG. 6 shows the top view of the unfolded infant chair of FIG. 1;

FIG. 7 shows the bottom view of the unfolded infant chair of FIG. 1;

FIG. 8 shows a right side view of the foldable infant chair of FIG. 1, the foldable infant chair being in a partially folded configuration; and,

FIG. 9 shows a perspective view of the foldable infant chair of FIG. 1, the foldable infant chair being in a fully folded configuration.

The broken lines represent portions of the article that form no part of the claim.
